(57) **CLAIM**

The ornamental design for a table base as shown and described.

DESCRIPTION

FIG. 1 is a top perspective view of my new table base; FIG. 2 is a bottom perspective view of the table base of FIG. 1;

FIG. 3 is a top view of the table base of FIG. 1; FIG. 4 is a bottom view of the table base of FIG. 1; FIG. 5 is a left-side view of the table base of FIG. 1; FIG. 6 is a right-side view of the table base of FIG. 1; FIG. 7 is a front view of the table base of FIG. 1; and, FIG. 8 is a rear view of the table base of FIG. 1. The broken lines in FIGS. 2, 4, 6, and 8 illustrate an environment that forms no part of the claimed table base.
